(57) **CLAIM**

The ornamental design for a buffet warmer, as shown and described.

DESCRIPTION

FIG. 1 is a front elevational view of a buffet warmer showing my new design;

FIG. 2 is a rear elevational view thereof;

FIG. 3 is a left side elevational view thereof;

FIG. 4 is a right side elevational view thereof; and

FIG. 5 is a top plan view thereof; and,

FIG. 6 is a bottom plan view thereof.

The electric cord shown broken away in the drawings is understood to represent indeterminate length.
